MILLARD J. BOYD, OF TORONTO, OHIO, ASSIGNOR TO FOLLANSBEE BROTHERS COMPANY, OF PITTSBURGH, PENNSYLVANIA, A CORPORATION OF PENNSYLVANIA

FURNACE FOR THE HEAT TREATMENT OF SHEETS

Application filed June 6, 1931. Serial No. 542,537.

This invention relates broadly to sheet normalizing furnaces, and more specifically to that type of continuous furnace in which the metal sheets are advanced through the 5 normalizing chamber on the peripheries of rotating disks.

The primary object of the invention is to provide, in a furnace embodying sheet-conveyor disks, simple and practical means 10 whereby, during operation, the peripheral carrying surfaces of said disks are constantly subjected to abrasion to the extent that they are maintained in a polished condition, or free from the formation thereon of the 15 usual "pin-head" projections and surface inequalities which might pit or otherwise mar the surfaces of sheets advanced thereon.

A further object is to provide a furnace of the character mentioned having beneath the 20 conveyor disks a floor or hearth upon which is maintained a loose bed of a suitable abrasive material having such depth that the lower portions of the peripheral surfaces of the disks are constantly embedded therein, 25 or at least have wiping contact therewith, for effecting removal therefrom by abrasion of foreign matter or deposits which, if permitted to remain and/or accumulate, would tend to pit or mark the surfaces of sheets traveling 30 thereover.

In describing the invention in detail, reference is herein had to the accompanying drawings, in which—

Figure 1 is a transverse section of a furnace, illustrating my invention, and—

Figure 2 is a longitudinal section of the front end portion of the same.

In said drawings, 1 designates the normalizing chamber of a furnace of the general type employed in the heat treatment of metal sheets. Such furnace embodies side walls 2, a floor or hearth 3, a crown 4, and a front end wall 5, the latter being provided with a door opening 6 through which the 45 sheets to be treated are introduced within said chamber 1.

Journaled for rotation within the furnace chamber is a plurality of transversely disposed relatively spaced shafts 7 having their 50 axes located in a common horizontal plane

and having fixed thereon spaced conveyor disks 8 adapted to transport forwardly on the peripheral surfaces thereof the metal sheets which are to be subjected to heat treatment.

The disks are disposed at a suitable elevation relative to the level of the floor or hearth 3, and carried on said hearth is a bed 9 of an abrasive material having a substantially uniform normal depth exceeding the 55 height of the undermost portions of said disks relative to said hearth.

While other abrasive materials may be employed in the formation of said bed 9, gravel, or a mixture of gravel and sand, is at present 60 preferred, the same being introduced within the furnace chamber by any appropriate means, as through one or more suitably located openings or passages 10 provided in the crown 4. As herein shown, a hopper-like 65 receptacle 11 is mounted over and in open communication with said passage and is adapted to receive and direct downward to and through said passage the material supplied thereto.

The rotating disks 8 serve to gradually advance and spread the abrasive material deposited, as aforesaid, within the furnace chamber forming a bed of approximately 70 uniform depth, which depth normally is 75 such that said disks are partially embedded in the material. So embedded, the entire peripheral, or sheet-carrying, surface of each disk is subjected, in each revolution of the latter, to frictional wiping engagement with 80 the abrasive material of the bed, resulting in maintaining said surface at all times in a smoothly polished condition.

Obviously, the material of the bed 9 is, by 85 the rotating action of the disks, gradually shifted toward the front end wall 5 of the furnace, thus producing a gradual lowering of the level of the top surface of said bed. To prevent the piling up against said front 90 wall of the abrasive material so advanced, an exit port or passage 12 is provided in said front wall at an appropriate elevation, through which said material may escape outwardly, as indicated in Fig. 2 of the drawings. This escaped material may from time 95 100

to time be collected and reintroduced in the furnace for re-use.

What is claimed is—

1. In a furnace for the heat treatment of metal sheets, the combination with rotating conveyor disks, of a bed of loose gravel having partially embedded therein peripheral portions of said disks.
2. In a furnace for the heat treatment of metal sheets, the combination with rotating conveyor disks, of a bed of loose abrasive material in which are embedded the undermost peripheral portions of said disks.
3. In a furnace for the heat treatment of metal sheets, the combination with rotating conveyor disks, of a bed of loose abrasive material in which are embedded the undermost peripheral portions of said disks, means in the furnace for introducing material for the formation of said bed, and a passage for egress of material from said bed following shifting thereof out of effective range of said disks.
4. In a furnace for the heat treatment of sheets, the combination with a furnace chamber and a succession of conveyor disks arranged over the hearth of said chamber, of a bed of loose abrasive material carried by said hearth, said bed having a substantially uniform normal depth exceeding the elevation of the undermost portions of the peripheries of said disks relative to said hearth.
5. In a furnace for the heat treatment of sheets, the combination with a furnace chamber and a succession of conveyor disks arranged over the hearth of said chamber, of a bed of loose abrasive material carried by said hearth, said bed having a substantially uniform normal depth exceeding the elevation of the undermost portions of the peripheries of said disks relative to said hearth, said chamber having therein a passage through which material of said bed may escape following shifting thereof past the last of said succession of disks.

In testimony whereof, I affix my signature.
MILLARD J. BOYD.
